FIG. 6 is a top plan view thereof;

FIG. 7 is a bottom plan view thereof;

FIG. 8 is a front left perspective view of a first embodiment of the convertible swaddle garment in an expanded position showing our new design, with the expanded portion having a first shape in the first embodiment;

FIG. 9 is front elevation view of the first embodiment;

FIG. 10 is a rear elevation view of the first embodiment;

FIG. 11 is a right side view of the first embodiment;

FIG. 12 is a left side view of the first embodiment;

FIG. 13 is a top plan of the first embodiment;

FIG. 14 is a bottom plan view of the first embodiment;

FIG. 15 is a front left perspective view of a second embodiment of the convertible swaddle garment in an expanded position showing our new design, with the expanded portion having a second shape in the second embodiment;

FIG. 16 is a front elevation view of the second embodiment;

FIG. 17 is a rear elevation view of the second embodiment;

FIG. 18 is a right side view of the second embodiment;

FIG. 19 is a left side view of the second embodiment;

FIG. 20 is a top plan view of the second embodiment;
FIG. 21 is a bottom plan view of the second embodiment;
FIG. 22 is a front left perspective view of a third embodiment of the convertible swaddle garment in an expanded position showing our new design, with the expanded portion having a third shape in the third embodiment;
FIG. 23 is a front elevation view of the third embodiment;
FIG. 24 is a rear elevation view of the third embodiment;
FIG. 25 is a right side view of the third embodiment;
FIG. 26 is a left side view of the third embodiment;
FIG. 27 is a top plan view of the third embodiment;
FIG. 28 is a bottom plan view of the third embodiment;
FIG. 29 is a front left perspective view of a fourth embodiment of the convertible swaddle garment in an expanded position showing our new design, with the expanded portion having a fourth shape in the fourth embodiment;
FIG. 30 is a front elevation view of the fourth embodiment;
FIG. 31 is a rear elevation view of the fourth embodiment;
FIG. 32 is a right side view of the fourth embodiment;
FIG. 33 is a left side view of the fourth embodiment;
FIG. 34 is a top plan view of the fourth embodiment;
FIG. 35 is a bottom plan view of the fourth embodiment;
FIG. 36 is a front left perspective view of a fifth embodiment of the convertible swaddle garment in an expanded position showing our new design, with the expanded portion having a fifth shape in the fifth embodiment;
FIG. 37 is a front elevation view of the fifth embodiment;
FIG. 38 is a rear elevation view of the fifth embodiment;
FIG. 39 is a right side view of the fifth embodiment;
FIG. 40 is a left side view of the fifth embodiment;
FIG. 41 is a top plan view of the fifth embodiment; and,
FIG. 42 is a bottom plan view of the fifth embodiment.
The broken lines of even length shown in the drawings illustrate portions of the convertible swaddle garment that form no part of the claimed design. The broken lines of uneven length define the boundaries of the claimed design.
